UNITED STATES PATENT OFFICE.

EDWARD F. CALDWELL, OF LARCHMONT, NEW YORK.

DESIGN FOR A BOX.

42,251.

Specification for Design.

Patented Mar. 5, 1912.

Application filed December 14, 1911. Serial No. 665,819. Term of patent 3½ years.

To all whom it may concern:

Be it known that I, EDWARD F. CALDWELL, a citizen of the United States, residing in Larchmont, in the county of Westchester and State of New York, have invented a new, original, and ornamental Design for Boxes, of which the following is a specification, reference being had to the accompanying drawings, forming a part thereof.

Figure 1 is a plan view of the top of a box, showing my new design; Fig. 2 is a side view of the box, showing my new design; and Fig. 3 is an end view of the box, showing my new design.

I claim—

The ornamental design for a box, as shown.

EDWARD F. CALDWELL.
